PORABLE SOUND MANIFOLD

Alan French, Warwick, and Arthur Edward Pryde, Providence, R.I., assignors to Avid Corporation, East Providence, R.I.

Filed July 31, 1972, Ser. No. 276,760

Term of patent 14 years

Int. Cl. D14—03

U.S. Cl. D26—14 G

FIG. 1 is a perspective view of a portable sound manifold, showing our new design;

FIG. 2 is a top plan view of FIG. 1;

FIG. 3 is a top plan view of the lower half section, with the top half section removed;

FIG. 4 is a side elevational view of FIG. 1, with a portion broken away so as to locate FIG. 3.

We claim:

The ornamental design for a portable sound manifold, as shown and described.
